UNITED STATES PATENT OFFICE.

LOUIS P. DISS, OF ILION, NEW YORK, ASSIGNOR TO E. REMINGTON & SONS,
OF SAME PLACE.

PACKING-CASE FOR CARTRIDGES.

SPECIFICATION forming part of Letters Patent No. 356,276, dated January 18, 1887.

Application filed July 22, 1886. Serial No. 203,819. (No model.)

To all whom it may concern:

Be it known that I, LOUIS P. DISS, of Ilion, in the county of Herkimer and State of New York, have invented certain new and useful Improvements in Packing-Cases for Cartridges, of which the following is a specification.

This invention relates to cases for carrying cartridges and charging magazines; and the invention consists in certain novel features of construction, as hereinafter more fully set forth.

Figure 1 is a side elevation, Fig. 2 a top plan view, and Fig. 3 a bottom plan view, of a case made on my plan. Fig. 4 is a side elevation of the same, slightly modified in form. Fig. 5 shows the manner of using the same in connection with a magazine-gun, the latter being shown in section.

The object of my invention is to produce a case in which cartridges can be packed and carried securely, and from which they can be readily transferred in a mass to the magazine of a gun of that class which has its magazine underneath the receiver, and from which the cartridges are fed sidewise up through an opening in the receiver.

To construct a packing-case on my plan I cut from thin sheet metal, pasteboard, or other suitable material a blank of such a form that when properly bent or folded it will form a case or box, such as is shown in Figs. 1, 2, and 3, these blanks being cut out in the general form or manner described and shown in my Patent No. 304,712, and varying therefrom only in minor details, which will be readily understood by persons skilled in the art after seeing a description of my improved case. The blank has a slot, J², cut or punched in it in such a position that when it is bent into the proper form to make the case J this slot J² will form an opening extending from near its lower edge up one side, as shown in Fig. 1, and nearly across the top, as shown in Fig. 2, there being left an unbroken strip, J³, along the side below the slot or opening J², for the purpose of strengthening and supporting the side wall, and keeping it and the edges along the slot in position and preventing them from being bent out of shape; and as these cases are designed to be made of the lightest material that will answer, this I consider an important feature.

The shape of the case which I prefer is that shown in Figs. 1, 2, and 3, it being of a width corresponding with that of the cartridges to be used, (and which varies with different guns,) and of such a length as to permit the cartridges to be placed therein, resting one upon another, with their flanges overlapping, as shown in Fig. 1, and which, as is well known, is the position they must occupy in the magazine in order to be fed into the gun properly. It will be seen that while the top and rear walls stand very nearly at a right angle to each other the front wall is more inclined, thus making the case gradually decrease in length from front to rear, from the top downward, when measured on a line parallel with the top wall, the front wall also being much shorter from top to bottom than the rear wall, as shown clearly in Fig. 1, thus adapting it to receive and hold the taper cartridges compactly. If, however, the cartridges be more or less tapering than those shown, then of course the case will be modified to correspond, the general construction, however, being the same.

At the lower end of the front wall I form an inwardly-inclined lip, a², as shown in Figs. 1 and 3, which serves two purposes, viz: first, it forms a rigid bearing for the heavier end of the cartridges, the bullet of the lower cartridge resting directly on it; and, second, and more important still, it acts as a retainer for the front end of the cartridges when they are forced out of the case into the magazine below, thereby causing the heads of the cartridges to pass from the case down into the magazine first, whereby they are caused to retain their proper relative positions, with the flange of the upper one in advance of the one next below, as shown in Fig. 5, and to occupy that position in the magazine without failure when thus transferred from the case J.

In order to retain the cartridges in the case when being transported, another lip, t, is secured to one side of the case, near its rear end, of such a length that it can be bent over the cartridge next to it, as shown in Fig. 3. Either or both of these lips t and a² may be formed integral with the walls of the case by leaving suitable projections on the edge of the blank when it is cut out; or they may be made separately and then be soldered or otherwise se-

cured to the case, as may be found most convenient in manufacture.

Fig. 4 represents a modification of the case, in which the front and rear walls are made ^{all} with each other and of uniform length; the case is shorter from front to rear than the cartridges, so that they must occupy a diagonal position therein, their front ends being supported by or resting on or against the front wall, as shown in Fig. 4, this front wall thus serving to support and retain the front ends of the cartridges in essentially the same manner as does the lip a^3 in Fig. 1. In this case the cartridges will lie parallel with each other, ¹⁵ their front ends resting against the front wall and their heads at one edge resting against the rear wall, as shown, the shortness of the case preventing them from assuming any other position therein. In this case, also, the angle ²⁰ of the top wall in relation to the rear wall is made a little more acute, as shown, in order to be sure that the flanges of the cartridges shall assume the required position one in advance of the other, the same as in the other case. It ²⁵ will at once be seen that the cartridges when forced from this case down into the magazine will have their front ends retained or held back by the front wall in essentially the same manner as by the lip a^3 in the other case, and ³⁰ that they will thereby be compelled to enter the magazine in the same manner and assume the same relative position in the magazine as they would when forced from the case shown in Fig. 1.

³⁵ The manner of transferring the cartridges

from the packing-case to the magazine is clearly shown in Fig. 5. To do this it is only necessary to straighten out the lip t , insert the mouth of the case J in the receiver directly over the magazine, and by inserting the thumb ⁴⁰ in the slot J^2 force the entire mass of cartridges directly down into the magazine M below.

It will of course be understood that the opening through the receiver will be of a size and shape to correspond with that of the cartridges, ⁴⁵ that the magazine will have its mouth made of a corresponding form, and that the receiver will be provided with spring-lips to hold the cartridges in the magazine after they are thus transferred; but as these features relate to improvements in the gun for which a separate application was filed July 22, 1886, Serial No. 208,818, they need not be described herein. ⁵⁰

Having thus described my invention, what I claim is—

1. A packing-case for cartridges, consisting of the box J , having the slot J^2 in its side and top walls, with the unbroken strip J^3 along its edge below the slot, substantially as shown and described. ⁵⁵

2. A packing-case for cartridges, consisting of the open-mouthed box J , provided with the slot or opening J^2 , the fixed lip a^3 at its front end, and the flexible lip t at or near its rear end, substantially as shown and described. ⁶⁰
